UNITED STATES PATENT OFFICE

1,927,491

BACKREST OR SUPPORT FOR A SEAT OR
THE LIKEArchibald Horsfield Gabb, Fishponds, Bristol,
England, assignor to The Tan-Sad Chair Com-
pany (1931) Limited, Birmingham, England, a
British companyApplication May 9, 1932, Serial No. 610,167, and
in Great Britain March 9, 1932

2 Claims. (Cl. 155—157)

The present invention has relation to a backrest or support for a seat or the like, and has for its object the incorporation of such a device adapted to be readily adjusted both with regard to height and inclination in a particularly simple and efficient manner.

According to the present invention the backrest or support is slidably accommodated in a two-part clamp carried by a link pivotally connected to the seat or other fixture, the said clamp being operable by means of a hand screw member provided upon the link and serving to maintain the support both with respect to its vertical and angular adjustment by co-operation with an arcuate-shaped fixed abutment associated with the seat frame.

In order that this invention may be clearly understood and readily carried into practice, reference may be had to the appended explanatory sheet of drawings, upon which:—

Figure 1 is a side elevation, and

Figure 2 a sectional plan view of a backrest or support for a seat or the like constructed according to the present invention.

In a convenient embodiment of the present invention the frame *a* for supporting the seat involves a hollow frame part *a*¹ protruding rearwardly. Pivoted within the fore part of the hollow frame upon a transverse spindle *a*² is a link in the form of a rod *b* on the rearward extremity of which a hand screw member *b*¹ is adapted to rotate. The rearward edge *a*³ of the hollow frame *a*¹ is of arcuate formation and its lower part is serrated or provided with teeth *a*⁴. Mounted upon the link *b* is a two-part clamp the forward part *d* being of channel formation and involving a bearing edge *d*¹ at its upper part adapted to co-operate with the arcuate plain part *a*³ of the hollow frame *a*¹ and a tooth *d*² at or about its lower part adapted to co-operate with the serrated or toothed arcuate lower part *a*⁴. *d*³ is a boss on the forward part of the clamp which slidely engages a vertical slot *a*⁵ (Figure 2) in the rear of the hollow frame *a*¹. The rearward part of the clamp is in the form of a plate *e* having a boss *e*¹ involving inclined or wedge faces *e*². Both parts of the clamp are apertured for the passage of the link *b* and the backrest or support in this invention involves

side by side upright bars *f* which are accommo-

dated between the respective parts of the clamp, as shown particularly in Figure 2, the wedge or inclined faces *e*² of the rearward part *e* operating between the limbs of the backrest or support *f*. The hand screw member *b*¹ co-operates with the elements of the clamp preferably through the medium of an intermediary washer. The upright bars *f* constituting the backrest or support are embraced by or incorporated within the channel-shaped forward element *d* of the clamp and a coiled compression spring *g* is interposed between the members of the clamp upon the link *b*, and a further coiled spring *h* is mounted upon the link *b* and interposed between the forward element *d* of the clamp and the boss *b*² constituting the pivotal bearing of the said link. The hand screw *b*¹ may screw upon the link *b* as shown or alternatively hand screw and link may be integral, in which case the latter is adapted to screw into a tapped aperture in the boss *b*².

In operation in order to adjust the backrest or support *f* the hand screw member *b*¹ is initially released, thereby spacing the elements of the clamp and permitting of the manual vertical adjustment of the said backrest or support. In order to adjust its inclination the pivotal link *b* is rocked by means of the hand screw member *b*¹ until such time as the backrest or support has assumed the desired inclination, after which the hand screw member *b*¹ is rotated to tighten the clamp and simultaneously bring the forward element *d* of the clamp into effective engagement with the serrated arcuate face *a*³ *a*⁴ of the hollow frame *a*¹ for maintaining the desired inclination.

What I claim as my invention and desire to secure by Letters Patent is:

1. A backrest for a seat comprising in combination a fixed hollow protuberance attached to the seat and having an arcuate and serrated extremity, a rod pivoted within said protuberance, clamping members provided upon the rod, a duplex upright member slidably mounted between the clamping members, a hand screw member provided upon the rod, and projections upon one of the clamping members adapted to co-operate with the arcuate and serrated face upon the protuberance.

2. A backrest for a seat comprising in combi-

nation a fixed hollow protuberance attached to the clamping members adapted to co-operate with the arcuate and serrated face upon the protuberance, and helical springs upon the rod adapted to assist in opening the components of the clamp. 80
